UNITED STATES PATENT OFFICE.

ALBERT EDWARD COTTON, OF EAST BRUNSWICK, NEAR MELBOURNE, VICTORIA,
AUSTRALIA.

MEANS FOR MANUFACTURING CASTINGS FOR SHAPING AND DRYING HOSIERY.

1,422,675.

Specification of Letters Patent. Patented July 11, 1922.

Application filed April 26, 1921. Serial No. 464,531.

To all whom it may concern:

Be it known that ALBERT EDWARD COTTON, a citizen of the Commonwealth of Australia, and resident of 21 Lydia Street, 5 East Brunswick, near Melbourne, in the State of Victoria, Commonwealth of Australia, has invented a certain new and useful Means for Manufacturing Castings for Shaping and Drying Hosiery, of which the following is a specification.

This invention relates to an improved means for manufacturing castings for shaping and drying stockings, socks and the like and has been specially devised in order to 15 overcome the defects in the method and castings at present employed.

In the method and means at present employed, no means have been provided to counteract the effect and pressure of the 20 steam as it is blown through the steam passage of the casting during the shaping and drying of the articles and in practice it has been found that even with only a thirty pound head of steam, the latter forces 25 through eruptions of the casting and blowing therethrough causes blisters on the articles being shaped or dried with a consequential loss of material as well as rendering the casting valueless until the holes are 30 plugged.

The invention has been devised in order to obviate existing defects in the drying and shaping of articles and to provide means whereby such defects are overcome in a 35 cheap, simple and effective manner and whereby the cost of upkeep, material and labour is reduced to an absolute minimum.

The salient feature embodied in this invention consists in the formation of a steam 40 passage or lining in the casting which will withstand a maximum pressure of steam and which will prevent the contact of the steam with the outer material forming the body of the casting by means of a metal tube 45 so fashioned and disposed within the casting that the steam circulates through the tube, so heating the casting in an even and effective manner.

A further essential feature embodied in 50 the invention consists in the method of shaping the steam tube or pipe; and in the method of mounting the same in the mould so as to prevent blowing blistering and any eruption in the casting.

55 A further essential feature consists in the

combination with a casting of metal or other suitable material for the purpose specified of a metal pipe or tube with a steam inlet and a steam outlet, the pipe being so disposed as to effectively impart the heat to 60 the casting or body for drying and shaping the articles carried thereby.

In order that the invention may be more readily understood it will now be described with reference to the accompanying drawings in which:—

Figure 1 is a view in plan of the improved steam pipe or tube mounted in position on one half of a mould preparatory to casting the mould shape.

70 Figure 2 is a view in plan of a die plate and the pipe or tube bent to shape.

Figures 3 and 4 are side and plan views respectively illustrating the finished casting with the steam pipe indicated by dotted 75 lines.

Figure 5 is a view illustrating an essential detail.

According to this invention, core boxes are dispensed with and a metal tube or pipe 80 *a* of suitable length is annealed to soften and after annealing the tube is filled with sand, wax or other filling and the ends are plugged to prevent creasing or bending when shaping. The pipe or tube *a* is then 85 bent to the shape indicated in Figure 2 on a die plate *b*.

The filling and plugs are then taken out and the pipe *a* is flattened more or less to suit the thickness of metal in the casting. 90

Preparatory to fitting into the bottom half of the mould *c* the tube *a* is again filled with sand *j* to allow of the heating of the tube *a* by a heater, the heat imparted being such that it is retained during the casting 95 operation to prevent blowing, blistering or any eruption that might otherwise take place in the casting if the tube *a* remained cold.

The shaped tube *a* is then inserted in position in the mould portion *c* which is filled 100 with sand and has one half of the pattern to be cast formed therein as at *d*.

The pipe *a* rests upon chaplets *e* buried in the sand in the bottom half of the mould *c* and also in the top half to prevent the 105 pipe *a* from rising and falling under the action of the molten metal. Suitable means *i* are provided in the mould near the top thereof to effect a pathway transverse to the ends of the pipe. A suitable gate or kit *f* 110

is provided in the mould to allow of the ingress of the molten metal.

After moulding the casting *g* to the shape required, according to the pattern employed as at *d* the casting after cooling is dressed while the ends *h* of the pipe *a* are punched to flare slightly outwardly to prevent ingress of steam between the pipe *a* and the casing *g* the pathway *i* allowing connection with the steam pipe from the source of supply.

It will be obvious that the tube *a* may be shaped slightly differently by being embedded closely within and around the edge 15 of the shape *g*.

I desire it to be understood that various modifications and improvements may be embodied without departing from the spirit and scope of the invention, for instance, the 20 body *g* may not be of metal but may be of

other suitable material which may be of earthenware, fire clay or the like, moulded, cast or impressed to the shape required and having the pipe *a* mounted therein.

What I claim as my invention and desire to secure by Letters Patent is—

A mould for the purposes specified having a steam passage formed by shaped piping therein; means at the top of the mould providing a pathway transverse to the ends 30 of the pipe, the ends of the pipe being also at the top of the mould and leading into the pathway substantially as described.

Signed at Melbourne, Victoria, Australia, this 24th day of March, 1921.

ALBERT EDWARD COTTON.

In the presence of—

A. EDWARD,
SIDNEY HENDLEY.
